United States Patent

Des. 235,164
Patented May 20, 1975

235,164

SPECTACLE TEMPLE

Anthony Shindler, Brookline, Mass., assignor to American Optical Corporation, Southbridge, Mass.

Filed Dec. 26, 1973, Ser. No. 428,160

Term of patent 14 years

Int. Cl. D16—06

U.S. Cl. D57—1 A

FIG. 1

FIG. 2

FIG. 3

FIG. 1 is a front perspective view of the spectacle temple embodying my new design showing the outer surface;

FIG. 2 is a rear perspective view thereof, showing the inner surface; and

FIG. 3 is an elevational view thereof.

I claim:

The ornamental design for a spectacle temple, as shown.
